UNITED STATES PATENT OFFICE.

HARRY JONES, OF SUFFERN, NEW YORK, ASSIGNOR TO EDWARD H. FALLOWS, OF NEW YORK, N. Y.

BRAKE-SHOE WITH CORRUGATED AND PERFORATED INSERT.

995,013.

Specification of Letters Patent. Patented June 13, 1911.

Application filed February 10, 1911. Serial No. 607,728.

To all whom it may concern:

Be it known that I, HARRY JONES, a citizen of the United States, and a resident of Suffern, in the county of Rockland and State of New York, have made and invented 5 certain new and useful Improvements in Brake-Shoes with Corrugated and Perforated Inserts, of which the following is a specification.

10 My invention relates to brake shoes of the type having a metallic insert of wrought metal, such as mild steel, embedded in the cast metal body portion of the shoe, and which insert is worn away simultaneously 15 with the body portion as the shoe is used; and the objects thereof are to provide a brake shoe in which the insert will contribute materially to the strength of the shoe; to provide a brake shoe in which the cast 20 metal body portion will be held together as a unitary structure should it become cracked or broken in use; to provide a brake shoe in which there is no waste of material in the formation of the insert; to provide a 25 brake shoe in which the insert and body portion are more firmly joined together as the cast metal body portion is poured about the insert; to provide a brake shoe in which the disposition of the cast metal of the body 30 portion and the wrought metal of the insert in the wearing face of the shoe is continuously changing as the shoe is worn away in use, so that the formation of grooves in the periphery of the car wheel with which the 35 shoe is used will be avoided, and to provide such other improvements in and relating to brake shoes of the type referred to as are hereinafter disclosed; all as illustrated in the accompanying drawing, described in 40 the following specification and particularly claimed in the clauses of the concluding claim.

In the drawing accompanying and forming a part of this specification; Figure 1 is a view in side elevation showing the insert in place within a shoe, the body portion being partly broken away to better show the form of the insert; Fig. 2 is a view showing the shoe as seen from a position in front 50 of its wearing face; Fig. 3 is a view showing a section upon a transverse plane indicated by the line 3—3, Fig. 1, and Fig. 4 is a view showing the back of the shoe.

In the drawing, 7 represents the wrought 55 metal insert of my improved brake shoe.

This insert is formed from a rectangular plate of metal such as mild steel the plate being corrugated as shown in Fig. 3 to provide comparatively deep grooves 8 extending longitudinally of and throughout the 60 length of the insert, the insert being bent or curved longitudinally so as to correspond, approximately, with the curvature of the car wheel with which the shoe is to be used. The sides of the insert 7 are crimped as 65 shown at 9 whereby undulating edges of the insert are produced, the crimping being preferably accomplished at the same time that the insert is curved longitudinally, although the edges may be crimped at a separate 70 rate operation.

The insert 7 is provided with longitudinally extending series of holes 10 preferably spaced uniformly along the bottom walls of said corrugations or grooves 8, said 75 holes being preferably formed by punching, in which case the punch is forced through the insert from the bottom wall or concave surface of the grooves, so that the material of the insert is displaced or forced outward 80 from the convex surface of the grooves or corrugations, the form of the punch being such that the material of the insert is displaced and formed into a bur 14, and not completely and cleanly cut out as is usual in 85 punching processes.

The term bottom wall is used, as will be understood, with reference to the position in which the corrugated insert is supported when the holes are being punched, the punch 90 being always driven from the concave surface of the corrugations, and the insert so supported that such surface becomes the bottom wall of the corrugation.

The body portion of the shoe is indicated 95 by the reference character 11, and the metallic insert 7 is located adjacent the front or wearing face of the shoe, as shown, so that the body portion of the shoe and the metallic insert are simultaneously worn 100 away when the shoe is in use.

In forming the shoe the metallic insert is placed in the mold and the fluid metal from which the body portion of the shoe is formed is poured about the insert, whereby it becomes 105 embedded in the cast metal body portion of the shoe. The fluid metal of the body portion flows through the holes 10 of the insert, and fills the corrugations or grooves 8, the cast metal body portion and the insert 110

being thus securely bound together, both because of the form or shape of the insert, and by the metal of the body portion which extends through the holes 10. The cast 5 metal body portion and the insert wear away simultaneously as the shoe is used, and the form of the insert is such that it contacts with different portions of the car wheel as the shoe is worn, whereby the formation of 10 grooves in the car wheel is avoided.

In practice my improved brake shoe will be formed with a wrought metal back stiffening member 12, and with a securing lug 13, both embedded in the cast metal body portion 15 of the shoe, said elements being placed in the mold with the insert before the body portion is formed. These elements, however, form no part of the invention disclosed and claimed in this present application.

20 It will be understood that the longitudinally extending and comparatively deep grooves or corrugations impart great strength to the insert as compared with the amount of metal contained therein, whereby 25 it follows that the shoe, in which the insert is embedded, is materially strengthened. Furthermore, the insert being of considerable volume at all points is not seriously burned by the fluid metal as it comes into 30 contact therewith, a source of weakness in a shoe wherein the insert are finely divided.

Having thus described my invention, I claim and desire to secure by Letters Patent:

1. In a brake shoe of the class described, 35 a cast metal body portion, and a wrought metal insert embedded in said body portion, and located adjacent the wearing face of the shoe so as to be worn away simultaneously with the body portion said insert extending 40 longitudinally of the shoe and being corrugated, the corrugations extending longitudinally of the insert.

2. In a brake shoe of the class described, 45 a cast metal body portion, and a wrought metal insert embedded in said body portion, said insert extending longitudinally of the shoe and being corrugated, the corrugations extending longitudinally of the insert, and the sides of said insert being crimped to provide 50 undulating edges.

3. In a brake shoe of the class described, a cast metal body portion, and a wrought metal insert embedded in said body portion, said insert extending longitudinally of the shoe and being corrugated, the corrugations 55 extending longitudinally of the insert, the latter having a series of holes spaced apart and located in the bottom walls of said corrugations.

4. In a brake shoe of the class described, 60 a cast metal body portion, and a wrought metal insert embedded therein, said insert extending longitudinally of the shoe and being longitudinally corrugated, having a series of holes spaced apart and located in the 65 bottom walls of said corrugations, said holes being punched from the concave surface of the bottom walls of said corrugations whereby a bur is formed upon the convex surface of said bottom walls.

70 5. In a brake shoe of the class described, a cast metal body portion, and a wrought metal insert embedded therein, said insert extending longitudinally of the shoe and being corrugated, the corrugations extending 75 longitudinally of the insert and the sides of said insert crimped to provide undulating edges, said insert having a series of holes spaced apart and located in the bottom walls of said corrugations.

6. In a brake shoe of the class described, 80 a cast metal body portion, and a wrought metal insert embedded therein, said insert extending longitudinally of the shoe and being corrugated, the corrugations extending 85 longitudinally of the insert, and the sides being crimped to provide undulating edges, said insert having a series of holes spaced apart and located in the bottom walls of said corrugations, said holes being punched from 90 the concave surface of the bottom walls of said corrugations whereby a bur is formed upon the convex surface of said bottom walls.

Signed at Suffern in the county of Rock- 95 land and State of New York this seventh day of February A. D. 1911.

HARRY JONES.
